DESIGN FOR A SHOE BUCKLE

David Levin, New York, N. Y.

Application October 4, 1935, Serial No. 58,830

Term of patent 3½ years

To all whom it may concern:

Be it known that I, David Levin, a citizen of the United States of America, residing in Manhattan, county of New York, and State of New York, have invented a new, original, and ornamental Design for a Shoe Buckle, of which the following is a specification, reference being had to the accompanying drawing, forming part thereof.

I claim:

The ornamental design for a shoe buckle substantially as shown.

DAVID LEVIN.
